UNITED STATES PATENT OFFICE.

JAMES E. SIMPSON, OF BROOKLYN, NEW YORK.

TYPE-WRITING MACHINE.

1,258,484.

Specification of Letters Patent.

Patented Mar. 5, 1918.

Application filed June 5, 1917. Serial No. 172,926.

To all whom it may concern:

Be it known that I, JAMES E. SIMPSON, a citizen of the United States of America, residing at the borough of Brooklyn, county 5 of Kings, State of New York, have invented a new and useful Improvement in Type-Writing Machines, of which the following is a specification.

This invention relates to typewriting machines and refers particularly to means for re-inking or moistening the ink ribbons employed therewith, so that the impressions produced on a work sheet in a machine may be uniform and of full body.

15 Operators of typewriting machines realize that the life of an inking ribbon is quite short, involving the necessity of frequent renewals, and they further realize that after a short usage, impressions received from the ribbon fail to present clearly printed characters, the work gradually becoming less distinct under continued usage of the ribbon, until finally the impressions are quite indistinct if the ribbon be left on the machine for too long a period.

Therefore I have devised means whereby, under the ordinary operation of the machine, the ribbon employed therewith may 30 be subjected to a process of continual revivification, whereby each character, word, and line of matter will be identical, in respect to the depth of color and clarity of impression imposed upon the work sheet.

35 The means employed by me in accomplishing the above stated object are simple in the extreme and both positive and continuous in operation. This means comprises the employment of an ink feed device which 40 may be in the form of an ink saturated wheel or disk, arranged to bear against one surface of the ribbon, and rotating with the ribbon spool under frictional contact between the inking device and the ribbon upon 45 the spool.

In practice, I have found it undesirable to leave the inking device in contact with the ribbon while the machine is at rest, because then there is a tendency to create an 50 excess deposit of ink upon the ribbon at the point of contact, which results in the production of heavier character impressions from that part of the ribbon, when in the type striking position. This objection is overcome by the provision of means whereby the operation of the inking device is au-

tomatically discontinued by being freed from contact with the ribbon each time the type bar returns to its bed after its type has created an impression, and by means 60 whereby the operation of a finger key automatically brings the inking device into contact with the ribbon.

Other features and advantages of my said invention will hereinafter appear. 65

In the drawings:—

Figure 1 is a perspective elevation showing a portion of a typewriting machine including an example of my invention applied thereto. 70

Fig. 2 is a detail plan view illustrating a portion of the mechanism for said inking device.

Fig. 3 is a plan view showing a portion of a machine frame with the re-inking device 75 operable with respect to both ribbon spools, and Fig. 4 is a detail of a bichrome inking-pad.

In the example of my invention illustrated in this application, I have shown an 80 inking-pad 1, in the form of a disk or wheel, as carried in a frame 2, which is mounted as by a pivot 2^a upon a portion 3 of a typewriting machine frame, and in proximity to a ribbon spool 4 carrying ribbon 5. The inking-pad 1 is mounted in the frame 2 as by a pivot 6, whose axis is parallel to the axis of the ribbon spool. The relation between the pad 1 and spool 4 is such that the periphery of the pad may come in 85 contact with the ribbon upon the spool, said contact being effected as under the tension of a spring 7 extending between the frame 2 and machine frame portion 3, whereby the inking-pad is swung into the aforesaid inking relation with the ribbon, in order that, as the spool 4 rotates, as under the influence of its feed mechanism 4^a, the ribbon thereon may move against the rotating peripheral surface of the inking-pad, to receive a supply 90 of ink therefrom. 100

It will be noted that the ink from the pad 1 is deposited upon that surface of the ribbon which receives impact from the types, the permeability of the ribbon being relied 105 upon to enable the deposited ink to create the impression of the type upon a worksheet, supported as by platen 3^a, when a type strikes the thus inked ribbon at the printing point. 11

Should the ribbon be inked at its side next the worksheet, the impression, under

the condition of a thus freshly inked ribbon, would be too heavy and smudgy. Practice has proven that inking the ribbon on its outer surface has little tendency to clog the types, due to the freshly moist condition of the ink as supplied by my method to the ribbon during the actual operation of the machine.

It is not necessary that the ribbon employed with my aforesaid inking device be what is known to-day as an ink ribbon, because the ink for the ribbon may be supplied entirely from the source or fountain represented by the inking-pad referred to. Therefore a plain or un-inked ribbon may be borne by the usual spools in a typewriting machine and its complete supply of ink imparted in the manner described. Thus my invention comprises a new method of supplying ink for the production of character impressions in a typewriting machine.

I have also found in practice that it is inadvisable to leave the inking-pad in contact with the ribbon surface while the machine is at rest, because such continued contact would have the effect of depositing too heavy a charge of ink upon the ribbon at that point, and would result, when that heavily charged portion of the ribbon reached the printing point, of making heavier type impressions from the ribbon. Therefore I have provided means to normally hold the inking-pad out of contact with the ribbon. The example of means whereby this phase of my invention is indicated herein consists of a dog or interponent 8, mounted by a pivot 9 in a bracket 10, which latter may be carried by the pivot 2. Normally the dog 8 is held between the opposed surfaces of the pad 1 and the ribbon 5 upon the spool, thus separating these members to prevent ink transference while the machine is inactive. The said dog 8 is held in this interposed relation by means of a spring 11, whose tension is greater than the tension of spring 7, said spring being shown as connecting the brackets 2 and 10 at points distant from their pivotal support.

It is necessary when the machine is operated for the production of a character impression, that the inking-pad be brought into operative inking relation with the ribbon, and therefore I have provided means, operable with the actuation of the finger keys, whereby the dog 8 is withdrawn from its interposed position, and whereby means, as the spring 7, may function to establish the desirable peripheral contact between the inking-pad and ribbon.

The means herein shown for accomplishing this result may consist of a vertical rod 12 loosely engaging with a universal bar 13, which may be mounted on pivotal arms 14 located beneath the key levers 15, so that when a character key is struck the universal

bar will be depressed and will exercise a pull upon the rod 12. Said rod 12 at its upper end, engages in a guide slot 16 in the bracket 2, and has an inclined face 17, which normally lies above the bracket 10, but which, in the movement or depression of the universal bar 13 and the downward pull of rod 12, is caused to bear against the inner edge of bracket 10 and thus to swing said bracket outwardly; in this act overcoming the tension of spring 11 and withdrawing the dog 8 from its separating position between the inking-pad and ribbon. Thus every down stroke of a key lever is caused to reestablish the operative contacting relation between the inking-pad and ribbon, so that a supply of ink is furnished to the ribbon intermittently. The intermittency of the ink supply synchronizes with the intermittency of the ribbon feed, because the ribbon feed progresses step by step under the operation of the finger keys, and also the inking-pad is put into operation with the ribbon under the same circumstances.

The universal bar 13, and the rod 12, may be returned after each of the operative strokes, as by means of a spring 13a. Probably in excessive speed operation of the machine the interponent mechanism will not have time, between the key strokes, to function in separating the inking-pad and ribbon, so that under high speed usage the contacting relation between the inking-pad and ribbon may be constant.

It is merely a matter of mechanical skill and adjustment for the universal bar 13 to have such relation with the finger keys, (which may include the spacer key), that said universal bar is actuated to perform its functions during a portion of the key lever stroke in advance of the actuation of the ribbon spools, so that the inking-pad may become seated against the ribbon just prior to the feeding movement of the latter, in order that the full extent of the movement of the ribbon may be communicated to the inking-pad, which thus is enabled to present new areas of its peripheral surface to the feeding ribbon.

Obviously I am not limited to the particular character of mechanism shown for achieving the stated result, nor to the particular location of parts indicated in the drawing.

An inking device should be provided in conjunction with each ribbon spool in order that it may be applicable to ink the ribbon in each direction of its feed. Good results however may be obtained by simply providing an inking device in conjunction with one of the spools.

The inking pad may be of any desirable character, such for example as felt or other absorbent of moisture, and should be saturated with moist ink of suitable consist-

ency to give the best results. In some instances, a moist pad without coloring matter may be used instead of an inking-pad, to revivify an ink ribbon.

5 When desired to provide for the inking and moistening of a bi-chrome ribbon I may substitute a double pad for the pad 1. The form of such double pad is shown in Fig. 4, wherein two like pads, as 18, 19, are arranged side by side, one bearing ink of one color and the other bearing ink of another color, to register, in use, the different colors respectively of a bi-chrome ribbon. These pads 18, 19, may be separated as by a plate 20.

10 15 As will be evident from the arrangement of the supporting and operative parts for the inking-pad and the relation of said pad with the ribbon spool, the inking-pad will continue to maintain a position whereby it can continue to have contacting relation with the ribbon upon the spool through the varying degrees of diameter which the ribbon has, as a roll upon the spool, as said ribbon becomes wound and unwound thereon, to be thus operative under all conditions of ribbon feed.

Whether the form in which my invention is employed requires the use of an inking means, or a moistening means without coloring matter, it will be appreciated that in either instance the effect produced will be that of revivifying the ribbon, which effect enables the ribbon to produce the desired clear and uniform type impressions.

35 While I have illustrated my ribbon inking means in conjunction with a typewriting machine, it is evident that the principle of invention herein involved is equally applicable to other machines employing character types to make impressions, through an ink ribbon, upon a work sheet; such for example as adding machines, addressing machines, stock tickers, and the like, all of which I consider, in so far as my invention is concerned, to come under the general term of typewriting machine.

I claim:—

1. In a typewriting machine, having keys, a ribbon, means for moving said ribbon, an ink supply, and means for imparting ink from said supply to said ribbon by the operation of the keys.

2. In a typewriting machine, having a ribbon support, a ribbon thereon, and means for feeding the ribbon across the printing point, the combination of a source of ink supply, and means controlled by the operation of the machine for intermittently communicating ink from said supply to said ribbon during the feeding movement of the latter.

3. In a typewriting machine, having a ribbon support, a ribbon thereon, means for

feeding the ribbon across the printing point, and a platen to support a work sheet and receive type impacts, the combination of a source of ink supply, and means controlled by the operation of the machine for intermittently communicating ink from said supply to said ribbon during the feeding movement of the latter.

4. In a typewriting machine, having a ribbon, means for moving said ribbon intermittently, an ink supply, and means controlled by the operation of the machine for intermittently imparting ink from said supply to said ribbon synchronously with the intermittent movements of the latter.

5. In a typewriting machine, having a ribbon, means for moving said ribbon intermittently, an ink supply, means for communicating ink from said supply to said ribbon during the intermittent movements of the latter, and means for withholding the communication of ink from said supply to said ribbon when the latter is not in motion.

6. In a typewriting machine, having a ribbon, means for moving said ribbon intermittently, an ink supply, means for pressing said ink supply into contact with said ribbon, to ink the latter, and means for releasing said ink supply from such contact.

7. In a typewriting machine, having a ribbon, means for moving said ribbon intermittently, a revoluble inking pad, means for pressing said pad in rolling contact with said ribbon, to ink the latter, and means for releasing said pad from such contact when the ribbon is inactive.

8. In a typewriting machine, having a ribbon, means for moving said ribbon intermittently, a finger key to actuate said ribbon moving means, inking means, means for applying said inking means to said ribbon, means for normally holding said inking means away from said ribbon during the inactivity of the latter, and means actuated by said finger key, to release said holding means and thus permit the operation of said means for applying said inking means, in synchronism with the intermittent movement of said ribbon.

9. In a typewriting machine, having keys, an inking ribbon, means for moving said ribbon, ribbon revivifying means, and means for applying the revivifying means to the ribbon by the operation of the keys.

In testimony whereof, he has signed his name to this specification in the presence of two subscribing witnesses, this first day of June, 1917.

JAMES E. SIMPSON.
